United States Patent Office

Des. 221,994
Patented Sept. 21, 1971

221,994

NUCLEAR RATE METER

Wayne J. Gemmill, Warwick, N.Y., assignor to Union
Carbide Corporation, New York, N.Y.

Filed Mar. 12, 1970, Ser. No. 21,869

Term of patent 14 years

Int. Cl. D10—11

U.S. Cl. D52—6

FIG. 1.

FIG. 2.

FIG. 1 is a front perspective view of a nuclear rate meter, showing my new design; and

FIG. 2 is a rear perspective thereof.

I claim:

The ornamental design for a nuclear rate meter, as shown.
